United States Patent Office.

JOHN H. BLAKE, OF WESTBROOK, ASSIGNOR TO HIMSELF AND J. M. TODD, OF PORTLAND, MAINE:

Letters Patent No. 95,309, dated September 28, 1869.

IMPROVED MEAT-CHOPPER.

The Schedule referred to in these Letters Patent and making part of the same.

To all whom it may concern:

Be it known that I, JOHN H. BLAKE, of Westbrook, in the county of Cumberland, and State of Maine, have invented a new and useful Improved Meat-Chopper; and I hereby declare the following to be a full, clear, and exact description of my invention, reference being had to the accompanying drawings, forming part of this specification, in which—

Figure 1 shows a side view of my invention.

Figure 2, a side view of spring-arm.

Figure 3, a front view of same.

The purpose of my invention is to furnish a new and improved device for chopping meat and other articles, as well as to provide a machine for cutting bait for fishing-purposes.

My invention consists—

First, in the combination and arrangement, upon a support or frame so constructed as to overhang the meat-receptacle, of the geared wheel *a*, with its crank, gear *b*, shaft *c*, balance-wheel *d*, the connecting-rod *e*, eccentrically pivoted to said balance-wheel, and the square rod or piston *f*, with the removable receptacle *g*.

Secondly, it consists of the devices above recited, in combination with the stud *h*, arm *i*, spring *j*, spring-pawl *k*, the ratchet *l*, and the spring *m*.

The support or frame of my machine is shown at *A*, so constructed as to project over the receptacle *B*, in order to the proper operation of the rod or knife-carrier *f*. This is effected by the parts 1 and 2, through which the rod operates.

By the revolution of gear *a*, by means of its crank, motion is communicated to the gear *b* and its shaft, and thence to the balance-wheel.

Upon this balance-wheel is the stud or projection *o*, over which loosely passes the upper end of the connecting-rod *e*. This rod is also pivoted to the upper end of the knife-carrier *f*, so that by the revolution of the balance-wheel, a vertical motion is communicated to the knife-carrier.

As the knife-carrier is moved up and down, it is held in position by the before-mentioned projecting parts 1 and 2. Through these, the holes are of such size as to allow of the turning of the rod as it moves up and down.

Upon the lower projection 2 is placed the horizontal ratchet *l*. The square rod passes through a square aperture in the centre of this ratchet, into which it fits exactly.

This horizontal ratchet is turned partially at every vertical motion of the rod *f*, or, in other words, at every revolution of the shaft *c*. This is effected by means of the stud *h*, arm *i*, spring *j*, and the spring-pawl *k*.

As the shaft *c* revolves, the upper end of the arm *i* is once during each revolution thrown off by the stud *h*, and, when the stud moves away from under the said

arm, the spring *j* restores the arm to its original position, the said arm being pivoted to the frame of the machine, at *p*. This motion of the arm, occasioned by the stud *h*, causes the spring-pawl *k* to push the ratchet *l* a distance represented by the spaces between the teeth on said ratchet at each revolution of the shaft *c*, or stroke of the rod *f*. Thus a rotary motion in a horizontal plane is imparted to the rod *f* and the knife *r*, which is attached to its lower end. Thus the knife has two motions—a vertical motion, and a rotary motion in a horizontal plane. The effect of this is, that with a sufficient number of revolutions, the knife traverses the entire area of the circular receptacle for the article to be chopped, and so comes in contact with the entire contents thereof.

The partial rotary motion which is given to the knife *r* does not take place until, by the revolution of the balance-wheel, it is lifted nearly out of the receptacle *B*, so that the contents thereof will not be disturbed by the partial revolution thereof, while the machine is moving rapidly.

The knife *r* is attached to the carrier *t* by means of the set-screws *v* and the slots *u* in the blade.

The carrier is attached to the rod *f* by means of the socket and thumb-piece *w*.

It can be seen that the knife-blade can be so gauged as not to strike, with too much force, the bottom of the receptacle *B*.

The receptacle *B* is removable, by the turning of the button *x*. This is convenient, for the purposes of cleansing, repair, &c.

From this explanation of the devices, it will be seen that an exceedingly rapid vertical motion is imparted to the knife, while, at the same time, it is automatically revolved, so as to bring all of the contents of the receptacle *B* under the edge thereof.

An ordinary flat dasher could, instead of a knife, be attached to the bottom of the rod *f*, and the operation of churning be rapidly executed, the rotary motion of the rod *f* aiding very much the production of the butter.

The spring *m* prevents the ratchet *l* from being moved too rapidly by the pawl.

The upper end of the rod *f* is made round, and fits into a circular hole in a square block of metal, *y*, and is secured therein, either by a head or pin. This admits of the rotating motion of the said rod.

The connecting-rod *e* is bifurcated at its lower end, and pivoted to the said block of metal, so as to admit of the required motions of the said rod *e*.

The patent of J. G. Hirzel is for the combination of knives, with an intermittent rotary knife-block, with a toothed rotating metallic rim, an arm, certain pawls, and a guide. Such a combination I hereby disclaim. I also disclaim F. S. Rutschman's combination, consisting of a frame, a shaft, a connecting-rod, a sliding

block, an adjustable cutting-bar, a cutter-frame, knives, a revolving block, a carrier, and a track. Also, I disclaim the combination of L. S. Starret, which is for certain driving-devices, with a false spring-bottom; the first-named patent being dated August 11, 1868, No. 80,955; the second, May 25, 1869, No. 90,588; the third, June 27, 1865, No. 48,458.

What I claim as my invention, and desire to secure by Letters Patent, is—

The described arrangement of gears *a* and *b*, shaft *c*, wheel *d*, projection *o*, rod *e*, joint *y*, toothed wheel *l*, parts *t* and *v*, arm *i*, spring *j*, projection *h*, on the shaft *c*, upon the frame *A*, as herein described.

JOHN H. BLAKE.
